UNITED STATES PATENT OFFICE.

MAY R. SMITH, OF BROOKLYN, NEW YORK.

DESIGN FOR A DOLL.

Application filed July 12, 1922. Serial No. 3,043. Term of patent 3½ years.

To all whom it may concern:

Be it known that I, MAY R. SMITH, a citizen of the United States of America, residing in the borough of Brooklyn, county of Kings, city and State of New York, have invented a new, original, and ornamental Design for Dolls, of which the following is a specification, reference being had to the accompanying drawing, forming a part thereof.

The figure is a perspective view of a doll illustrating the design of the invention.

I claim:

The ornamental design for a doll substantially as shown.

In witness whereof, I have hereunto signed my name.

MAY R. SMITH.
